QUICK RELEASE BUCKLE

Charles John, Jr., Astoria, and Jules A. Kaufman, Bronx, N.Y., assignors, by mesne assignments, to Phillips-Van Heusen Corporation, New York, N.Y., a corporation of New York

Filed Jan. 25, 1963, Ser. No. 253,792

2 Claims. (Cl. 24—230)

This invention relates to a quick release buckle. It relates particularly to a quick release buckle intended for use with safety belts of the type worn by occupants of automobiles and aircraft.

It is an object of this invention to provide a quick release buckle having no selective mode of connection; that is, a buckle of which the normally separable elements or assemblies may be connected or latched together without regard to any twisting of either or both of the safety belt portions to which they are attached.

It is another object of the invention to provide a quick release buckle having two latch pawl elements pivotably positioned on a mounting plate member with a single spring element also positioned on said mounting plate tending to maintain both of said latch pawl elements in latching attitude.

It is another object of this invention to provide a quick release buckle having a plurality of latch pawl elements pivoted on a mounting plate member with the latch pawl elements being separately engageable with and requiring individual actuation for disengagement from a latch element to minimize the possibility of accidental release of the buckle.

It is another object of this invention to provide a quick release buckle having at least one latch pawl element pivoted on a mounting plate member, this latch pawl element being characterized by a high mechanical advantage under manipulation by the buckle wearer to allow easy disengagement of the latch pawl element from a latch element, and, correspondingly, easy release of the buckle even though the buckle be loaded heavily through the safety belt portions to which it is attached.

These and other objects and advantages of the present invention as well as its nature and substance will be more clearly perceived and fully understood by referring to the following description and claims taken in connection with the accompanying drawings in which:

FIG. 1 represents a side elevation view of the quick release buckle of this invention with the normally separable elements or assemblies of the buckle in separated or disconnected condition;

FIG. 2 represents a partly exploded view of the latch retaining assembly of the quick release buckle shown in FIG. 1;

FIG. 3 represents a view in section through the quick release buckle shown in FIG. 1 taken along line 3—3 therein looking in the direction of the arrows;

FIG. 4 represents a view in section through the quick release buckle shown in FIG. 1 taken along line 4—4 therein looking in the direction of the arrows;

FIG. 5 represents a view in section through the quick release buckle shown in FIG. 1 taken along line 5—5 therein looking in the direction of the arrows;

FIG. 6 represents a side elevation view of the quick release buckle of this invention generally similar to the showing of this buckle in FIG. 1, but with the cover sectioned away from the latch retaining assembly of the buckle;

FIG. 7 represents a side elevation view of the quick release buckle of this invention generally similar to the showing of this buckle in FIG. 6, but with the latch element and latch retaining assembly of the buckle having

2

been pushed together into engaged or connected condition; and

FIG. 8 represents a side elevation view of the quick release buckle of this invention generally similar to the showing of this buckle in FIG. 7, but with the latch element of the buckle being disengaged from the latch pawl elements and partly withdrawn from (or partly inserted into) the latch retaining assembly of the buckle.

Referring now to the drawings in detail, especially to FIGS. 1, 2, 3, 4, and 5 thereof, the quick release buckle of this invention generally designated 10 comprises a right hand or latch element generally designated 12 and a left hand or latch retaining assembly generally designated 14. As shown in FIG. 1, latch element 12 is attached to a safety belt portion 16, while latch retaining assembly 14 is attached to a complementary safety belt portion 18. Adjustment of the overall length of the safety belt is made in a manner well known to the art through manipulation of standard clamp or buckle 20 adjacent latch retaining assembly 14 of quick release buckle 10.

Latch retaining assembly 14 includes a mounting plate generally designated 22 to which are spot welded or riveted a pair of latch element guide blocks generally designated 24 and 26 and a latch pawl seat generally designated 28. Pivotably fitted in and to seat 28 are latch pawls generally designated 30 and 32 which tend to be maintained spread apart by action of double-leaf or hairpin-type spring 34 which is secured around an up-turned portion 36 of the mounting plate 22. The mounting plate is also characterized by up-turned portions 38, 40 and 42 against which latch element guide blocks 24 and 26 and latch pawl seat 28 are located respectively. Additionally mounting plate 22 is characterized by horizontal leg portions 44 and 46 having up-turned portions 48 and 50 at their respective outer ends. A belt adjustment bar motion limiting bar 52 is formed with or welded across the leg portions of the mounting plate. Also included in latch retaining assembly 14 are belt adjustment bar 54 around which safety belt portion 18 passes; cover 56 which makes sliding engagement on and over mounting plate 22 and the buckle parts positioned thereon, and screw 58 whereby cover 56 is detachably connected to mounting plate 22.

Referring next to FIG. 6, latch element 12 is separated from but oriented and aligned for entry into latch retaining assembly 14. The latch element includes two prong or horizontal leg portions 60 and 62. These leg portions are characterized respectively by outer guide surfaces 64 and 66, inner guide surfaces 68 and 70, and latching engagement surfaces 72 and 74. Latch element guide blocks 24 and 26 are characterized respectively by inner guide surfaces 76 and 78. Latch pawl seat 28 is characterized by outer guide surfaces 80 and 82. Guide surfaces 76 and 78 are spaced to permit and provide a fairly close sliding fit of guide surfaces 64 and 66 inside of them, and guide surfaces 80 and 82 are spaced to permit and provide a fairly close sliding fit of guide surfaces 68 and 70 outside of them as leg portions 60 and 62 of latch element 12 are inserted into latch retaining assembly 14.

Latch element leg portions 60 and 62 are of essentially identical size and shape although configured oppositely. The arrangement of guide blocks 24 and 26 and latch pawl seat 28 is symmetrical about a horizontal axis along the centerline of the guide block seat. Accordingly, assuming that either safety belt portion 16 or 18 were given a half twist, the leg portions of latch element 12 could still be inserted into latch retaining assembly 14 with leg portion 60 passing between guide block 26 and latch pawl seat 28 and leg portion 62 passing between the latch pawl seat and guide block 24.

Latch pawls 30 and 32 are rather generally L-shaped,

At their one ends they are provided respectively with rounded, knob-like portions 84 and 86 which are adapted to have close turning fits within the arcuate cut-out regions of latch pawl seat 23. At their other ends, latch pawls 30 and 32 are provided respectively with finger-pressure and motion-stop pieces 88 and 90. These pieces bear against inside surfaces or edges of cover 56 as shown in FIG. 6 to arrest the outward motions of the latch pawls under the influence of spring 34. Pieces 88 and 90 are characterized respectively by manipulation surfaces 92 and 94 accessible through cut-out regions in cover 56 and against which thumb or finger pressure may be exerted by the wearer of quick release buckle 10 to rotate the latch pawls inwardly against the force of spring 34. It is to be noted that each latch pawl requires separate manipulation or thumb or finger pressure application to be rotated inwardly. Said in other words, inward rotation of one latch pawl will not by itself cause such rotation of the other latch pawl.

Latch pawls 30 and 32 are characterized respectively by guide surfaces 96 and 98. These surfaces may be brought into essential alignment respectively with guide surfaces 80 and 82 on the latch pawl seat as the latch pawls are rotated inwardly. A condition of such alignment is shown, for example, in FIG. 8. Latch pawls 30 and 32 are also characterized respectively by latching engagement surfaces 100 and 102.

Referring next to FIG. 8, and supposing that latch element 12 is moving to the left with respect to latch retaining assembly 14 as indicated by the arrow above the latch element, latch element leg portions 60 and 62 have entered part way into the latch retaining assembly from their condition of being completely withdrawn shown in FIG. 6. The penetrating movement of the latch element leg portions has caused their leading ends to bear upon guide surfaces 96 and 98 of latch pawls 30 and 32 and, owing to the initial inclination of these surfaces, rotate the latch pawls inwardly against the force of spring 34.

Referring next to FIG. 7, latch element 12 has been moved as far as possible to the left with respect to latch retaining assembly 14. This final movement, that is, movement of the latch element to the left with respect to the latch retaining assembly from its, the latch element's, position relative thereto shown in FIG. 8, has caused inner guide surfaces 68 and 70 on latch element leg portions 60 and 62 to completely override guide surfaces 96 and 98 on latch pawls 30 and 32, with the result that the latch pawls have been allowed to be rotated outwardly under the influence of spring 34 to bring latching engagement surfaces 100 and 102 on the latch pawls in behind latching engagement surfaces 72 and 74 on the latch element leg portions. Quick release buckle 10 comprising latch element 12 and latch retaining assembly 14 is now in latched condition, and, short of an actual breakage of parts, is not susceptible to becoming unlatched by any pull on safety belt portions 16 and 18 however heavy.

Referring finally to FIGS. 7 and 8, quick release buckle 10 is unlatched or released by exerting inward pressure on manipulation surfaces 92 and 94 of thumb-pressure pieces 88 and 90 on latch pawls 30 and 32. Even though safety belt portions 16 and 18 be heavily loaded, the thumb-pressure pieces can be depressed easily to rotate the latch pawls inwardly. This is because of the high mechanical advantage that latch pawls 30 and 32 provide to a buckle wearer exerting pressure on surfaces 92 and 94 to rotate the latch pawls inwardly over any moments on these pawls tending to rotate them outwardly exerted by even very heavy loading on safety belt portions 16 and 18 acting through latch element leg portions 60 and 62. On the other hand, both of the latch pawls must be ro-

tated inwardly to permit release of buckle 10. Inward rotation of only one of them is not sufficient for this purpose. The double latching effect of latch pawls 30 and 32 coacting with latch element leg portions 60 and 62 minimizes the possibility of accidental release of the buckle through inadvertent or random depressing of the thumb-pressure pieces or one of them.

Once thumb-pressure pieces 88 and 90 have been depressed sufficiently far to bring latching engagement surfaces 100 and 102 on the latch pawls in clear of latching engagement surfaces 72 and 74 on the leg portions of latch element 12, quick release buckle 10 is effectively released, and its latch element 12 may be moved to the right away from its latch retaining assembly 14. Such movement is indicated by the arrow below the latch element in FIG. 8.

Protection by Letters Patent of this invention in all its aspects as the same are defined in the appended claims is sought to the greatest extent that the prior art allows.

What is claimed is:

1. A quick release buckle comprising, a latch element consisting of a plate adapted to be connected to a first safety belt portion, said latch element having two substantially parallel leg portions projecting from it, said leg portions having latching engagement surfaces near their ends, a latch-retaining assembly including a base plate and a closure plate thereover, said plates defining a shallow substantially rectangular housing into which the leg portions on the latch element are inserted through an open entrance end of the housing, the base plate having a loop engaged by a second belt portion, the base plate having a separating element mounted on it adjacent to said open end, which separating element is disposed between the leg portions when such leg portions are positioned in the housing, said separating element having arcuate recesses in its opposite edges, a pair of pawls disposed in the housing, each pawl having a rounded nose at one end fitted in one of the recesses and permitting pivotal movement of the pawl, each pawl having a notch for engagement by one of the latching surfaces on the legs, each pawl having an integral finger piece, each pawl being generally L-shaped in configuration, the housing having apertures through which said finger pieces are accessible, and a wish-bone type spring fitted on the base plate and having legs engaging the pawls and pivotally biasing them away from one another.

2. A quick release buckle as provided for in claim 1, wherein the noses of the pawls and the recesses in which said noses are located are positioned closer to the entrance opening in the housing than are the notches in the pawls, and said notches in the pawls are engaged by the latching engagement surfaces on the legs at positions behind the pivotal points of the pawls, said spring normally urging each pawl finger piece into engagement with a wall portion of the housing defining a respective one of each of the apertures, and said spring, recesses and wall portions forming the sole means for retaining the pawls in said housing.
